UNITED STATES PATENT OFFICE.

EMANUEL J. ALFIERES, OF NEW YORK, N. Y.

FORM FOR SETTING VAULT LIGHTS.

Application filed July 18, 1924. Serial No. 726,806.

This invention relates to forms for setting vault lights, by which title is meant in this application the devices shown and described for accurately and quickly placing the lenses and their encircling frames in proper spaced positions to receive the surrounding fixative body of cement by which the lenses and their frames are permanently held.

The object of this invention is the production of forms for the purpose mentioned, and which are of special construction and arrangement believed to enable any piece of work to be more expeditiously and conveniently performed than may be accomplished by whatsoever means employed with which this applicant is acquainted.

Of the accompanying drawings illustrating this invention, Figs. 1, 2 and 3 represent top plan views of several equally preferred and used shapes of the same form. Fig. 4 is a sectional view showing a lens in its frame and in engagement with the form and surrounded by the cement in its final position. Fig. 5 shows a lens in a modified form of frame, engaging the form illustrated in Fig. 2. Fig. 6 shows a section similar to Fig. 5 illustrating a lens in another shape of frame and engaging the form illustrated in Fig. 3. Fig. 7 is a top plan view of a number of associated hexagonal forms which are sometimes used. Otherwise these forms are the same as set out in Fig. 3.

Throughout the drawings and description the same letter is used to refer to the same part.

Considering the drawings, the form A in Fig. 1 has a square outline externally, and a rectangular opening *a*. The form A is not necessarily square in contour, but may be rectangular, such as the form *a'* with more than a single opening. It may be stated here, that the forms while shown in this application as made of rubber, may be fashioned of any other selected material which will render the service expected of them. They may be of fibre, or of wood, or of any of the various compositions of materials known at present. The forms are arranged evenly upon the supporting board with their edges in contact. It will be understood that the forms are removable. They may be taken away one at a time. As shown in Figs. 2, 3 and 7, it is usual in practice to have one form for each lens, each form being separately removable as stated. If the lenses are small, it is believed to be within the pur-

view of this invention to seat two lenses in the form.

In Fig. 2 it will be observed that the form B has a circular opening *b*, and that there is an adjacent shoulder *C* bordered by the annular ridge *c*.

In Fig. 3, the form D has the circular opening *d* bordered around the edge of the opening by the ridge *d'*.

Considering Fig. 4 it will be noted that the lens E is supported by the usual board *e* employed in setting vault lights of the character described, and the lower portion of the lens E is shown as passing through the opening *a* in the form A. The forms A are arranged upon the board *e* edge to edge as delineated in Fig. 1. The lens E is shown as seated in a frame F, so shaped as to afford a suitable seat for the enlarged upper portion of the lens, and about the lower part of the lens which passes through the open frame F, and in contact with the frame is the clamping band *f*. The clamping band is shown as of rubber, but the invention is in no sense confined to any particular material or form of band. Stout composition, fabric or even leather could be employed. The function of the clamping band is to hold the lens and frame together in proper spaced relation. It will be observed that when the lens and frame are clamped together and the lens is placed in engagement with the opening of the form plate A, the position of the lens and frame is fixed, and after the desired number of lenses have been thus located, the cement filling G and *g* may be applied to finally hold the lenses in place. Thereafter, the board *e* is removed, and the forms A also removed to be used over again.

It may be stated here that the kind of reinforcing rods, bars or other irons constitute no part of this invention, and any method of reinforcing may be employed together with the use of this invention.

In Fig. 5, the lens H has its lower portion resting upon the board *h*, while the frame J which encloses the lens is resting upon the form B. The lower end of the lens engages the opening *b* in the form B, and the lower end of the frame J engages the shoulder *C* of the form adjacent to the opening as illustrated. Any number or shape of external fins *j* may be provided upon the outside wall of the frame to fix the frame in the cement filling K, in the customary manner. The

lens is secured in the frame by means of the cement filling *k*.

In Fig. 6 the lens *L* is shown with its lower part or mouth engaging the ridge *d'* of the opening *d* in the form *D*, which is supported by the board or boards *l* and is removable with the boards as explained hereinabove. The lens frame *M* is of the same character as the frame *F* described in connection with Fig. 10. 4. It is made with a seat for the enlarged upper part of the lens *L*, and around the lower portion of the lens and in contact with the lower surface of the frame *M* is the clamping band *m* having the same function and capable of being made of any chosen materials as already explained. The band *m* remains in the cement filling *N*, but the forms *D* are removed when the cement has set. The lens is secured by the filling *n* in the manner common in such structures, and while the word cement is used in this description, it will be understood to mean any materials employed for this purpose.

The operation of this invention is believed to have been made clear in the foregoing explanation. The clamping band holds the lens and frame together in proper attitudes one with respect to the other, and when the forms are arranged upon the supporting board, the lenses may be quickly and accurately positioned. After the filling has sufficiently set, and the supporting boards removed, there is no difficulty at all found in taking off the forms for like use in other jobs.

Having now described this invention, and explained the manner of its operation, what I claim is:—

1. In a vault light setting, the combination with a removable flat support, of a plurality of flat forms carried by the said sup-

port and removable therefrom, the said forms being arranged in contact one with another to make a covering for the said support, each of the said forms having an opening, which opening engages a lens, the axes of same and of the opening being coincident. 45

2. In a vault light setting, the combination with a removable flat support, of a plurality of flat forms carried by the said support, the said forms being arranged in contact one with another to make a covering for and removable from the said support, each of the said forms having an opening, which opening engages and supports lenses and 55 lens frames, the axes of the same and of the opening being coincident.

3. In a vault light setting, the combination with a lens having an enlarged upper portion, of an open lens frame having a seat for 60 the said upper portion of the lens, the said lens having a lower portion passing through the frame, and a clamping band arranged upon the lower portion of the lens below the frame and in contact with the frame to hold 65 the lens and frame together.

4. In a vault light setting, the combination with a lens having an enlarged upper portion, of an open lens frame having a seat for the said upper portion of the lens, the lower portion of the lens passing through the said frame, a clamping band arranged upon the lower portion of the lens below the frame and in contact with the frame to hold 70 the lens and frame together in spaced relation, and cement filling securing the lens in the frame and surrounding the said frame and the said band and the said lower portion of the lens. 75

In testimony whereof I affix my signature.

EMANUEL J. ALFIERES.
